The present invention incorporates by reference U.S. Patent application Ser. No. 11/410,764 filed Apr. 25, 2006, which is a continuation-in-part of U.S. Patent application Ser. Nos. 11/020,183 filed Dec. 27, 2004 and 11/020,231 filed Dec. 27, 2004, all of which are also incorporated herein by reference.

FIG. 1 is a perspective view of a towel warming device showing my new design;

FIG. 2 is a front elevation view of a towel warming device showing my new design;

FIG. 3 is a top plan view of a towel warming device showing my new design;

FIG. 4 is a side elevation view of the towel warming device showing my new design; and,

FIG. 5 is a back elevation view of the towel warming device showing my new design.

In the drawings, the broken lines depict environmental subject matter only and form no part of the claimed design.
